Primary Examiner — Paul Allen Greene*(74) Attorney, Agent, or Firm* — Oblon, McClelland, Maier & Neustadt, L.L.P.(57) **CLAIM**

The ornamental design for a sound to vibration converter, as shown and described.

DESCRIPTION

FIG. 1 is a perspective view of front, bottom and left side of a sound to vibration converter showing our new design; FIG. 2 is a perspective view of front, top and right side thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 4 Drawing Sheets(56)
